CLAIM

The ornamental design for a ladder safety device, as shown and described.

DESCRIPTION

FIG. 1 is a perspective right front view of ladder safety device showing our new design;

FIG. 2 is a top plan view thereof;

FIG. 3 is a right elevational plan view thereof;

FIG. 4 is a left elevational plan view thereof;

FIG. 5 is a front elevational view thereof;

FIG. 6 is a rear elevational plan view thereof; and,

FIG. 7 is a bottom plan view thereof.

The broken lines shown in the figures are for the purpose of illustrating portions of the ladder safety device and from no part of the claimed design.

1 Claim, 6 Drawing Sheets

FIG. 2
